WEB GUIDING DEVICE

William C. Nash, Neenah, Wis., assignor of one-fifth to Mary Jones and one-fifth to Marie Duval Nash, both of Neenah, Wis., one-fifth to William M. Nash, Chicago, Ill., and one-fifth to Roy A. Nash, New Rochelle, N. Y.

Application May 1, 1935, Serial No. 19,157

3 Claims. (Cl. 242—76)

This invention relates to improvements in web guiding or aligning devices, and has more particular reference to means for maintaining the lateral edges of a continuously passing web of substantially flexible material in relatively constant vertical alignment.

More specifically the invention is directed to the provision of means of automatically maintaining the lateral edges of a continuously passing web of paper, felt, cloth or similar flexible material in a constant, straight line during its feeding or passage from a roll or other source of supply.

It is among the objects of the present invention to provide means which will effectively avoid objectionable creasing, folding or distortion of the traveling web due to lateral displacement of the web from a normal path; provide means which will effectively and completely readjust the traveling web and divert it beyond a predetermined point from such normal path, and to effect such readjustment of the web automatically and without interference to or impairment of the function or operation of the machine as a whole and its associate parts.

Other objects and advantages of my invention will be apparent from the following detail description and accompanying drawings wherein for purposes of exemplification a preferred embodiment thereof is shown.

In the drawings, Fig. 1 is a side elevational view of my invention as used in conjunction with a roll from which a flexible web is continuously fed forwardly.

Fig. 2 is a vertical sectional view illustrating my improved means for aligning said web.

Fig. 3 is a detailed elevational view of the feeler and switch mechanism associated with the web aligning device.

Fig. 4 is a sectional view taken on line 4—4 of Fig. 3.

Fig. 5 is a fragmentary, elevational view of a guide roll which may be actuated by my improved device whereby the edges of a traveling web may be maintained in constant alignment.

Fig. 6 is an end elevational view of the device shown in Fig. 5.

Fig. 7 is a schematic wiring diagram showing the electrical connections pertinent to my web aligning device.

Referring in detail to the drawings, 1 indicates a standard which is adapted to serve as a supporting medium for a bearing 2. A shaft 3 is adapted to be journalled at one of its ends in bearing 2 and the opposite end of said shaft is adapted to be journalled in a similar bearing supported upon a similar standard (not shown). The upper surface of standard 1 may be recessed in order to slidably receive bottom plate 4 of bearing 2. The plate 4 may be provided with

opposite extensions or flanges 5 which are adapted to register with undercut portions of the side walls of the recesses in the standard 1 so that plate 4 may be slidably positioned within said recess but would be prevented from moving vertically. A mandrel 6 may be mounted upon each end of shaft 3 between the supporting bearings, said mandrel being adapted to support a roll 7 of relatively flexible web-like material from which a web 8 may be fed forwardly. The roll 7 may comprise, for example, a roll of paper and a web 8 may, for instance, be fed forwardly to a printing press, saturating tank, re-winder, or the like. A brake drum 9 may be mounted upon shaft 3 and may be circumscribed by an adjustable brake band 10 which may carry a friction brake lining 11. In mechanisms of this character the braking device is utilized to prevent excess of freedom of rotation of roll 7. An arm 12 may be formed integral with plate 4 and may extend downwardly from said plate. A bracket 13 may be mounted upon one face of the standard 1 which is adapted to support a screw 14 which may be rotatably positioned in said bracket. The arm 12 may be apertured intermediate its length, said aperture being internally threaded to register with the threads of screw 14. A hand-wheel 15 may be mounted upon the end of screw 14 whereby said screw may be manually rotated.

Assuming, for example, that the web 8 is to be fed forwardly to a mechanism (not shown) which latter is characterized in that it is essential that the lateral edges of said web during the feeding operation be maintained in substantially constant alignment. It is further assumed that no particular care was taken in initially winding said roll so as to maintain the lateral edges of the web in a fixed plane. This is the usual procedure in initially winding, for instance, a paper web after the same comes from the dryers or calenders of a paper machine. Confronted with this problem, it has been the practice to maintain the lateral edges of the web 8 fed from the roll 7 in substantially constant alignment by manually manipulating hand-wheel 15 whereby screw 14 may be rotated in one direction or the other. It is obvious that when said screw is rotated, plate 4 will be shifted to the right or to the left as the occasion demands. Collars 16 may be mounted upon shaft 3 upon each side of bearing 2, said collars being rigidly secured to said shaft by means of pins 17. Consequently, when plate 4 is moved to the right or left as viewed in Fig. 1, shaft 3 and hence mandrel 6 and roll 7 will be correspondingly moved to the right or left whereby the lateral edges of the web 8 may be maintained in constant alignment. This type of mechanism is conventional and forms no part of my present invention. My invention, however, contemplates automatic means for shift-

ing shaft 3 longitudinally in order to maintain the lateral edges of web 8 in a fixed constant path.

A supporting column 18 may be positioned adjacent standard 1 and may carry at its upper end a platform 19 to which is secured a housing 20 by means of bolts 21 or other like securing means. The housing 20 may be of rectangular section and is preferably totally enclosed. An electric motor 22 may be mounted upon platform 19 and may be secured thereto by means of bolts 23 or the like. Motor 22 may be provided with the usual shaft 24 one end of which may project through a wall 25 of housing 20. Within housing 20, shaft 24 may carry a spur gear or pinion 26. Shafts 27 and 28 may be suitably journaled within housing 20, the longitudinal axis of said shafts being parallel and spaced on each side of shaft 24. A spur gear or pinion 29 may be mounted upon shaft 27 in such position thereon as to mesh with pinion 26. Similarly a spur gear 30 may be mounted upon shaft 28 and may mesh with a diametrically opposite portion of spur gear or pinion 26. As will be hereinafter more fully described, motor 22 is adapted to be maintained in continuous operation while web 8 is being fed forwardly. Consequently, inasmuch as gears 29 and 30 are constantly in mesh with pinion 26, said gears are also continuously rotated. However, inasmuch as gears 29 and 30 mesh with pinion 26 upon opposite sides of said pinion, said gears are rotated in opposite directions relative to each other and inasmuch as gears 29 and 30 are rigidly mounted upon respectively shafts 27 and 28, said shafts are continuously rotated in opposite directions.

Opposite side walls 31 and 32 of housing 20 may carry bearings 33 and 34 in which a shaft 35 may be journaled. A plate 36 may be secured 40 to the exterior surface of the side wall 32 by means of rivets 37 or the like, said plate carrying a projecting bearing portion 38. A sprocket wheel 39 may be mounted upon the end of shaft 35 which latter projects through wall 32 and 45 through the bearing portion 38.

A collar 40 may be mounted upon shaft 35 and may be freely rotatable thereon, said collar being spaced from bearing 33 by means of a thrust ball bearing 41. A similar collar 42 may 50 be freely rotatable upon shaft 35 and may be spaced from bearing 34 by thrust ball bearing 43. Collar 40 may be rigidly secured to a worm wheel 44 and similarly collar 42 may be secured to worm wheel 45. A worm pinion 46 may be rigidly mounted upon shaft 28 above spur gear 30. In 55 a similar manner a worm pinion 47 may be mounted upon shaft 27. The positions of worm pinions 46 and 47 upon shafts 28 and 27 respectively is such that said worm pinions respectively mesh with the threaded peripheries of worm wheels 44 and 45.

It can readily be seen that as shafts 27 and 28 are rotated, pinions 47 and 46 will be similarly rotated and inasmuch as said pinions mesh respectively with worm wheels 45 and 44, said worm wheels will also be rotated about shaft 35. However, since shafts 27 and 28 are rotating in opposite directions, worm wheels 45 and 44 will also rotate in opposite directions.

70 A solenoid 48 may be mounted upon one side of platform 19 and a similar solenoid 49 may be mounted upon the opposite side of said platform. Associated respectively with each solenoid 48 and 49 is a plunger or armature 50 and 51. 75 A lever 52 rigidly secured to shaft 53 which, in

turn, is journaled in wall 25 of housing 20, may be pivotally connected at opposite ends to the upper portions of plunger 50 and 51. A flanged bracket or angle-iron 54 may be secured to the outer face of side 25, the flange of said member being apertured at opposite ends through which apertures rods 55 and 56 may extend. A nut 57 may be mounted upon the lower end of rod 55 and a coil spring 58 may be confined between said nut and the lower face of the flanged portion of bracket 54, similarly a nut 59 may confine coil spring 60, both of which are associated with rod 56. The upper end of rod 55 may be pivotally connected as at 61 to an intermediate portion of lever 52 on one side of shaft 15 53. Similarly the upper end of rod 56 may be pivotally secured to lever 52 as at 62 upon the opposite side of shaft 53.

The arrangement is such that when solenoid 48 is energized, the flux set up by said solenoid 20 causes plunger 50 to move downwardly. This action of plunger 50 causes lever 52 to rotate in a clockwise direction thereby rotating shaft 53 and compressing spring 60. When solenoid 48 is de-energized, lever 52 moves to its normal 25 or horizontal position under the influence of the compressed spring 60. In like manner if solenoid 49 is energized, plunger 51 will be drawn downwardly and the lever 52 will be rocked in a counter-clockwise direction thereby rotating shaft 53 30 in a counter-clockwise direction and compressing spring 58. When solenoid 49 is de-energized, spring 58 causes lever 52 to return to its normal horizontal position.

Shaft 53 projects through wall 25 into the 35 interior of housing 20. A yoke 63 may be carried by shaft 53 within housing 20 and may be rigidly secured to said shaft, the opposite terminations of said yoke being positioned upon each side of shaft 35. Collar 64 may be slidably 40 but non-rotatably keyed to shaft 35 whereby said collar has limited longitudinal movement upon said shaft. The outer surface of collar 63 may be provided with an annular groove or recess 65 into which the opposite ends of yoke 63 45 may be positioned.

A face of collar 40 may be provided with annularly disposed ratchet teeth 66. In like manner a face of collar 42 may be provided with ratchet teeth 67. Opposite faces of collar 64 may 50 carry ratchet teeth 68 and 69. The teeth 66 and 68 are inclined in the same direction. Similarly teeth 67 and 69 are inclined in the same direction. However, teeth 66 and 68 are inclined in a direction opposite to teeth 67 and 69.

Reverting to the operation of solenoids 48 and 49 in conjunction with their function of rocking lever 52 and hence shaft 53, it can readily be seen that when shaft 53 is rocked in one direction, teeth 69 carried by collar 64 engage with teeth 60 67 carried by collar 42, and when shaft 53 is rocked in the opposite direction, teeth 68 carried upon the opposite face of collar 64 engage with teeth 66 carried upon the face of collar 40. As has been hereinbefore described, collars 40 and 65 42 are continuously rotated inasmuch as worm wheels 44 and 45 are respectively secured to said collars and, further, that said collars are rotated in opposite directions. Consequently, it can readily be seen that when collar 64 is so moved 70 as to cause the engagement of teeth 67 and 69, shaft 35 will be rotated in one direction. In like manner, when shaft 53 rocks in the opposite direction so as to engage teeth 66 and 68, shaft 35 will be rotated in the opposite direction. In view 75

of the fact that collar 64 is moved longitudinally along shaft 35 in either direction and bears with force against either collar 40 or 42, excessive friction or binding is prevented by the provision of the thrust bearings 41 and 43. Moreover, in view of the fact that the movement of collar 64 to neutral or central position is dependent upon springs 58 or 60 it is desirable that the pitch or the angular inclination of the ratchet teeth 66, 68, 67 and 69, that is, the angle A, be correlated with respect to the load upon said ratchet teeth. For instance, said angle may vary between 15 and 50°, the heavier the load the greater the angle. If the angle A is not correlated with respect to the load difficulty may be experienced in causing the ratchet teeth to disengage under load conditions, since the normal pressure of said teeth with respect to each other, increases as the angle of inclination A of said teeth decreases.

Referring particularly to Figs. 3 and 4, means is illustrated whereby solenoids 48 or 49 are energized when web 8 shifts in a lateral direction. Said means comprises an electric switch 10 which may include an arm 71 pivoted at 72, said arm carrying a cross member 73. An electric terminal 74 may be carried at the lower face of one end of the cross member 73 and a similar electric terminal 75 may be carried at the lower face of the opposite end of said member. A contact terminal 76 may be positioned adjacent terminal 74 and in like manner a contact member 77 may be positioned adjacent terminal 75. In normal position contacts 74 and 75 are respectively spaced from contacts 76 and 77, and arm 71 is positioned in substantially a vertical plane.

A palm or feeler 78 may be pivotally secured to the end shaft or rod 71, said rod being bifurcated at its lower end and terminating in bearing portions 79 and 80. A flanged plate 81 may be carried upon the inner face of the palm 78 and a rod 82 may be journalled in the flanges of said plate. Rod 82 also passes through the apertured ends of the bifurcated member forming the lower extension of rod 71. A coil spring 83 may embrace pin 82, the ends of said spring being associated with palm 78 and rod 71, as shown best at 84.

Switch 10 may be mounted adjacent the path of travel of web 8 in such manner as to cause palm 78 to contact one lateral edge of said web, said palm being maintained in contact with the lateral edge of the web by means of counter-weight 71' which may be adjustably mounted upon rod 72' which, in turn, may be connected to rod or arm 71. The normal path of travel of the edge of the web adjacent palm 78 may be so correlated with respect to rod 71 as to position contacts 74 and 75 in spaced relationship with respect to contacts 76 and 77.

Referring particularly to Fig. 7, it will be seen that cross member 73 in normal position is spaced from contact terminals 76, and 77 when palm 78 is so positioned as to have its contact surface in coincidence with the normal path of travel of the web. A' indicates schematically a source of electric current. One terminal of said source may be connected to the cross arm 73, or more strictly speaking, one source of electric current may be connected to both contacts 74 and 75 as illustrated in Fig. 3. The opposite terminal of said electric current source may be connected to one side of each of the solenoids 48 and 49. The terminal 76 may be connected to the opposite end of solenoid 48 and the terminal 77 may

be connected to the opposite end of the remaining solenoid 49.

In operation, as web 8 passes forwardly and tends to shift in a lateral direction, for instance, to the right as viewed in Fig. 3, palm 78 and rod 5 71 will be rocked in a counter-clockwise direction about pivot 72. This will complete an electric circuit through contacts 74 and 76, or referring to Fig. 7, an electric circuit will be completed from one terminal of the source A' through cross member 73, contact 76 and solenoid 48. In this manner, referring to Fig. 1, solenoid 48 will attract plunger 50 which will rock lever 52 in a clockwise direction. As viewed in Fig. 2, rod 53 will rock yoke 63 in a clockwise direction and, 15 consequently, the ratchet teeth of collar 64 will make engagement with ratchet teeth 67 and shaft 35 will be rotated in a predetermined direction. The rotation of said shaft will, in turn, cause the rotation of sprocket wheel 39. A 20 sprocket chain 85 operatively connects sprocket wheel 39 and a sprocket wheel (not shown) rigidly connected to screw 14. In this manner screw 14 will be so rotated as to move shaft 3 to the left so as to return the lateral edge of the web 25 8 to normal position. When the edge of web 8 is returned to normal position, switch 10 returns to normal position and, consequently, the circuit of solenoid 48 will be broken. Spring 60, 30 being subjected to compression by the rocking of lever 52, will now urge said lever to normal position and, consequently, the slidble collar 64 will be returned to normal position and shaft 35 will be maintained stationary. If web 8 moves in the opposite direction, that is, to the left, 35 weight 71' will cause palm 78 to follow the movement of the edge of said web thereby connecting terminals 75 and 77 together and completing an electric circuit through solenoid 49. When said solenoid is energized a similar operation takes 40 place wherein shaft 35 is rotated in the opposite direction and shaft 3 is so shifted as to move web 8 back to its normal position. In this manner a balance is obtained wherein lateral movement of web 8 toward either side of normal position will cause an operation which tends to shift the roll 7 to immediately return said web to its normal position.

It will be noted that palm 78 is so pivotally connected to rod 71 that it is free to move against the tension of spring 83 in a counter-clockwise direction about pin 82, as viewed in Fig. 3. By this provision, if an abnormal shift of web 8 to the right occurs, palm 78 or the associated switch mechanism will not be injured since the excess movement of the palm will be taken up by spring 83 after the upper portion 73' of rod 71 contacts screw 74' threadedly mounted in lug 75'. A similar screw 76' mounted in a similar lug 77' is positioned upon the opposite side of the upper 60 end 73' of rod 71. The arc of the swing of rod 71 is governed by the setting of screws 74' and 76'. However, portion 73' does not contact either of said screws until terminals 75 and 77 or 74 and 76 are in contact. In this type of switch 65 terminals 74 and 75 are resiliently mounted and sufficient "give" is obtained to permit the later contact of portion 73' and either of the screws 74' or 76'. The strength of spring 83 is so correlated with weight 71' that movement of rod 71 70 and hence weight 71' takes place before spring 83 is flexed. Of course, weight 71' may be substituted by a spring (not shown) which may normally urge rod 71 and palm 78 toward web 8, or switch 10 may be so mounted as to cause rod 71 75

and palm 78 to contact web 8 directly under the influence of gravity.

Referring particularly to Figs. 5 and 6, means for guiding a passing web 86 is illustrated, which means may be controlled by a mechanism similar to that shown in Figs. 1 and 2 to maintain the lateral edges of said web traveling in constant alignment. 86 indicates a guide roll carried by shaft 87 which may be journalled at one end in 10 a bearing (not shown) which is free to swing or rotate horizontally. The opposite end of shaft 87 is journalled in bearing 88 carried by and formed integral with casting 89. A guide rail 90 may be disposed upon the top of frame 91 and casting 15 88 may be provided with a groove or recess 92 whereby said casting may be slidably movable upon the top of frame 91 and may be guided by rail 90. A screw 93 may be journalled in the ends of frame 91 and may be threadedly associated 20 with casting 89 which may be provided at its lower end with rollers 94 which may support said casting upon the surface 95 of frame 91.

This construction is more or less conventional and is used to guide or control the lateral movement of a traveling web. In use the guide roll 86' is placed beneath the web 86 intermediate the path of travel of said web. To maintain the web traveling true, one end of roll 86', namely that end adjacent bearing 88, may be shifted 30 longitudinally with respect to the web. Movement of the roll in this manner causes the web to creep to the right or left depending upon the direction of movement of the bearing 88 and, therefore, said web may be maintained in constant alignment by appropriately shifting said bearing.

In utilizing my invention in conjunction with an arrangement of this type, sprocket chain 85 may be adapted to drive sprocket wheel 96 mounted upon screw 93. A palm and switch similar to that shown in Fig. 3 may be associated with the web 86 and may actuate the solenoids 48 or 49 whereby chain 85 may drive sprocket wheel 96 to revolve screw 93 and move bearing 88 in 45 the proper direction to cause the web to return to normal position.

Switch 70 forms no part of my invention per se and may be similar in construction to that described in United States Patent No. 1,960,020. 50 Consequently, a detailed description of said switch is deemed unnecessary.

Of course, the electric circuit shown in Fig. 7 is merely diagrammatic and suggestive of a circuit which may be used.

55 I claim as my invention:

1. A device for automatically maintaining the lateral edge of a continuously advancing flexible web in substantially constant alignment which comprises, means for shifting said web laterally, and means for actuating said web shifting means when said web moves laterally from its normal path, said actuating means comprising a pair of continuously oppositely rotating clutch members, a shaft upon which said members are freely rotatable, a cooperating clutch member slidably but non-rotatably mounted upon said shaft, means actuated by lateral displacement of the web from its normal path for engaging said cooperating clutch member and one of said continuously 60 rotating clutch members to rotate said shaft in the direction of said last mentioned clutch member, said engaging means comprising a solenoid, an electric switch connected in the solenoid circuit, a feeler disposed adjacent the path of travel of the web and movable with transverse movement of the web to throw said switch and energize said solenoid, a plunger associated with said solenoid, means operatively connecting said plunger and cooperating clutch whereby said cooperating clutch is moved into engagement with one of said clutch members, means operatively connecting said shaft and said web shifting means, and means associated with said plunger for returning said plunger to normal position and disengaging said cooperating clutch when said solenoid is de-energized.

path of travel of the web and movable with transverse movement of the web to throw said switch and energize said solenoid, a plunger associated with said solenoid, means operatively connecting said plunger and cooperating clutch whereby said cooperating clutch is moved into engagement with one of said clutch members, and means operatively connecting said shaft and said web shifting means.

2. A device for automatically maintaining the lateral edge of a continuously advancing flexible web in substantially constant alignment which comprises, means for shifting said web laterally, and means for actuating said web shifting means when said web moves laterally from its normal path, said actuating means comprising a pair of continuously oppositely rotating clutch members, a shaft upon which said members are freely rotatable, a cooperating clutch member slidably but non-rotatably mounted upon said shaft, means actuated by lateral displacement of the web from its normal path for engaging said cooperating clutch member and one of said continuously 10 rotating clutch members to rotate said shaft in the direction of said last mentioned clutch member, 15 said engaging means comprising a solenoid, an electric switch connected in the solenoid circuit, a feeler disposed adjacent the path of travel of the web and movable with transverse movement of the web to throw said switch and energize said 20 solenoid, a plunger associated with said solenoid, means operatively connecting said plunger and cooperating clutch whereby said cooperating clutch is moved into engagement with one of said clutch members, means operatively connecting 25 said shaft and said web shifting means, and means associated with said plunger for returning said plunger to normal position and disengaging said cooperating clutch when said solenoid is de-energized.

3. A device for automatically maintaining the lateral edge of a continuously advancing flexible web in substantially constant alignment which comprises, means for shifting said web laterally, and means for actuating said web shifting means when said web moves laterally from its normal path, said actuating means comprising a pair of continuously oppositely rotating clutch members, a shaft upon which said members are freely rotatable, a cooperating clutch member slidably but non-rotatably mounted upon said shaft, means actuated by lateral displacement of the web from its normal path for engaging said cooperating clutch member and one of said continuously 40 rotating clutch members to rotate said shaft in the direction of said last mentioned clutch member, 45 said engaging means comprising a solenoid, an electric switch connected in the solenoid circuit, a feeler disposed adjacent the path of travel of the web and movable with transverse movement of the web to throw said switch and energize said 50 solenoid, a plunger associated with said solenoid, means operatively connecting said plunger and cooperating clutch whereby said cooperating clutch is moved into engagement with one of said clutch members, means operatively connecting 55 said shaft and said web shifting means, and means associated with said plunger for returning said plunger to normal position and disengaging said cooperating clutch when said solenoid is de-energized.

WILLIAM C. NASH.
